UNITED STATES PATENT OFFICE.

JOSEPH BENJAMIN CATHY, OF GODFREY, GEORGIA.

HOLDING DEVICE FOR RESETTING SCRAPERS.

974,644.

Specification of Letters Patent.

Patented Nov. 1, 1910.

Application filed May 12, 1910. Serial No. 560,973.

To all whom it may concern:

Be it known that I, JOSEPH BENJAMIN CATHY, a citizen of the United States, and a resident of Godfrey, in the county of Morgan and State of Georgia, have invented a new and Improved Holding Device for Resetting Scrapers, of which the following is a full, clear, and exact description.

My invention relates to holding devices 10 for resetting scrapers, and it has for its object to provide one which may be manufactured at little cost, so that all farmers and blacksmiths may procure, at little expense, means for shaping and resetting scrapers 15 after they have been sharpened. When the scrapers are sharpened, after they become dull, they are usually so out of shape that they are of very little value until they are reset.

20 While the subject of this application has been especially devised for resetting scrapers used in cultivating cotton fields, it will be understood that the resetting devices may be used for other forms of scrapers.

25 Still other objects of the invention will appear in the following complete description.

In this specification I will describe the preferred form of my invention, it being 30 understood that the scope of the invention is defined in the appended claims.

Reference is to be had to the accompanying drawings forming a part of this specification, in which similar characters of reference indicate corresponding parts in all the views, and in which—

Figure 1 is a side elevation of the invention; Fig. 2 is a side, sectional elevation of the invention; Fig. 3 is an end view of the invention; Fig. 4 is a sectional view on the line 4—4 of Fig. 2; Fig. 5 is a sectional view on the line 5—5 of Fig. 2; Fig. 6 is a fragmentary, plan view of the base member showing the shaping plates; Fig. 7 is a perspective view of the clamping rod; and Fig. 8 is a perspective view showing one of the scrapers, to reset which my device has been devised.

By referring to the drawings, it will be 50 seen that the base member 6 has transverse supports 7, a frame being mounted on the base member 6, and consisting of a horizontal member 8 and legs 9 and 10, which are secured to the base member 6 and which 55 support the said horizontal member, two pairs of the legs 9 being disposed at one end

of the horizontal member 8 and one pair of the legs 10 being disposed at the other end of the horizontal member 8. The inner pair of legs 9 has lugs 11, to which is pivoted a 60 lever 12, the lever 12 having the terminal of one of its arms 13 disposed at substantially right angles to its other arm 14. A foot member 15 is secured to the base member 6 at a central portion, the said foot member 65 being bent at each side of its central portion, so that its sides are disposed upwardly, parallel to each other, the sides being disposed one at each side of the horizontal member 8 and being disposed forwardly, 70 and being secured thereto at 16, as shown in the drawings. The lower portion of the foot member is disposed forwardly and downwardly to the point where it is secured to the base member. Pivoted to the terminal 75 of the arm 14 of the lever 12, is a clamping rod 17, the clamping rod 17 being disposed rearwardly between the sides of the foot member 15, the rear terminal of the clamping rod 17 being shaped into a depending 80 flange 18, which is disposed at an acute angle relatively to the body of the clamping rod. The forward side of this depending flange 18 is provided with a lug 19. To the base member 6 are secured two clamping 85 plates 20, these clamping plates being also disposed at an angle to each other, the apex of which is disposed in the direction of the legs 9. The depending flange 18 is adapted to move between these clamping plates 20. 90 Connecting the terminal of the arm 13 of the lever 12 with the clamping rod 17, there is a lifting rod 21, so that when the arm 13 is moved upwardly, it will raise the clamping rod 17. 95

The base of the foot member 15 is disposed in a position corresponding with a similar part in a scraping machine to which the scraper plates are normally secured and, when the resetting device is in use, the 100 scraper 22 is disposed immediately behind this foot member, with the lug 19 of the depending flange 18 disposed, from the rear, through the opening 23 in the scraper 22. The arm 13 of the lever 12 is raised when 105 the scraper 22 is placed in position behind the base of the foot member 15, and when the arm 13 is moved downwardly, it draws the clamping rod 17 forwardly, thereby forcing the scraper 22 against the base of 110 the foot member 15, the scraper resting on the base member 6 or being disposed in close

proximity thereto. To secure the best results, the scraper 22 is heated before it is placed in position between the foot member 15 and the depending flange 18 of the clamping rod 17, and while it is still hot and held in position against the base of the foot member 15, the sides of the scraper 22 are hammered down and rearwardly against the shaping plates 20 until they lie flat against 10 the said shaping plates. As will be seen by referring to the drawings, these shaping plates not only are disposed at angles to each other, but they are inclined rearwardly and upwardly, so that when the sides of the 15 scraper 22 are hammered flat against the said plates, the scraper will be reset to its normal position, thereby permitting of the attainment of the best results when the scraper is again mounted on the machine 20 and is in use.

To free the scraper 22 from my device, the arm 18 of the lever 12 is raised, which raises the clamping rod 17 and moves it slightly rearwardly, by which means the scraper 22 25 is disengaged therefrom.

I prefer to construct the horizontal member 8, the base member 6 and the transverse member 7 of wood and the other parts of my device of metal, and I also prefer to bolt 30 the parts together as shown in the drawings, but it will be understood that these features are not material to my invention, as the parts of the device may be constructed of any suitable material and may be secured together in any firm manner.

Having thus described my invention, I claim as new and desire to secure by Letters Patent:

1. In a holding device for resetting scrapers, a base member, a shaping plate secured thereto, a frame secured to the base member, a foot member secured to the frame, a lever fulcrumed to the frame, a clamping rod articulated to the lower arm of the lever and extending past the foot member and in the direction of the shaping plate, and a depending flange on the clamping rod for engaging the face of a scraper in the direction of the shaping plate and drawing it in 50 the direction of the foot member.

2. In a holding device for resetting scrapers, in combination with a scraper, a base member, a shaping plate secured thereto, a frame secured to the base member, a lever pivoted to the frame, a clamping rod articulated to an arm of the lever and extending in the direction of the shaping plate, and means on the clamping rod for engaging the side of the scraper in the direction of the 55 shaping plate.

3. In a holding device for resetting scrapers, in combination with a scraper, a base member, a frame secured thereto, a foot member secured to the frame, a shaping 60 plate secured to the base member and spaced

from the foot member, a lever fulcrumed to the frame, a clamping rod articulated to an arm of the lever and extending past the foot member and in the direction of the shaping plate, and means on the clamping rod for engaging the scraper and holding it against the foot member and away from the shaping plate. 70

4. In a holding device for resetting scrapers, in combination with a scraper, a base member, a frame secured thereto, a foot member with an opening therethrough, secured to the frame, a shaping plate secured to the base member and spaced from the foot member, a lever fulcrumed to the frame, a clamping rod articulated to an arm of the lever and extending through the opening in the foot member and in the direction of the shaping plate, and means on the clamping rod for engaging the scraper and holding it 75 80 85 against the foot member.

5. In a holding device for resetting scrapers, in combination with a scraper, a base member, a frame secured thereto, a foot member secured to the frame, a shaping plate secured to the base member and spaced from the foot member, a lever fulcrumed to the frame, a clamping rod articulated to an arm of the lever and extending past the foot member and in the direction of the shaping plate, the other arm of the lever being bent so that the terminals of the arms of the lever are disposed substantially at right angles to each other, a rod connecting the said other terminal of the lever and the clamping rod, and means on the clamping rod for engaging the scraper and holding it against 90 95 the foot member with a surface of the scraper facing the shaping plate. 100

6. In a holding device for resetting scrapers, in combination with a scraper, a base member, a frame secured thereto, a foot member with an opening therethrough, secured to the frame, the foot member extending forwardly toward its lower end, a shaping plate secured to the base member and spaced from the foot member, a lever fulcrumed to the frame, a clamping rod articulated to an arm of the lever, disposed through the opening in the foot member and in the direction of the shaping plate, the other arm of the lever being bent so that the terminals of the arms of the lever are disposed at angles to each other, a rod connecting the said other arm of the lever and the clamping rod, and means on the clamping rod for engaging the scraper and holding it against the foot member with a surface of the scraper facing the shaping plate. 110 115 120

7. In a holding device for resetting scrapers, in combination with a scraper, having an opening, a base member, a frame secured thereto, a foot member with an opening therethrough, secured to the frame, a shaping plate secured to the base member and 125 130

spaced from the foot member, a lever fulcrumed to the frame, a clamping rod articulated to an arm of the lever and extending through the opening in the foot member and 5 in the direction of the shaping plate, a flange on the clamping rod, and a lug on the flange adapted to be disposed in the opening in the scraper for holding the scraper against the foot member with a 10 surface facing the shaping plate.

8. In a holding device for resetting scrapers, in combination with a scraper having side portions, a base member, a frame secured thereto, a foot member having an 15 opening therethrough, secured to the frame, two shaping plates disposed at angles to each other, spaced from the foot member and secured to the base member, a lever fulcrumed to the frame, a clamping rod articulated to an arm of the lever, the clamping rod extending through the opening in the 20 foot member and in the direction of the shaping plates, and means carried by the clamping rod for engaging the scraper, with 25 its sides facing the plates respectively.

9. In a holding device for resetting scrapers, in combination with a scraper having sides and an opening through its central portion, a base member, a frame secured 30 thereto, a foot member having an opening therethrough, secured to the frame, two

shaping plates disposed at angles to each other, spaced from the foot member and secured to the base member, a lever fulcrumed to the frame, a clamping rod articulated to an arm of the lever and extending through the opening in the foot member and in the direction of the shaping plates, a flange secured to the clamping rod, and a lug on the flange adapted to be disposed through the 35 opening in the scraper for holding the scraper against the foot member, with its sides facing the shaping plates respectively.

10. In a holding device for resetting scrapers, a base member, a foot member having an 40 opening therethrough, secured to the base member, a shaping plate secured to the base member and spaced from the foot member, a lever, a clamping rod articulated to an arm of the lever and disposed through the opening in the foot member and in the direction of the shaping plate, and means on the clamping rod for engaging a scraper for holding it in place against the foot member.

In testimony whereof I have signed my 45 name to this specification in the presence of two subscribing witnesses.

JOSEPH BENJAMIN CATHY.
